UNITED STATES PATENT OFFICE

2,471,425

DEVICE FOR CONTROLLING THE RELEASE
OF HIGH-PRESSURE FLUID MEDIUMS

Harry C. Grant, Jr., New York, N. Y., and Arthur E. Reichard, North Arlington, N. J., assignors to Specialties Development Corporation, Bloomfield, N. J., a corporation of New Jersey

Application January 13, 1944, Serial No. 518,070

19 Claims. (Cl. 74—479)

1

The present invention relates to control devices, and more particularly to a locally and remotely operable device or control head for controlling the release of a high pressure fluid medium.

In systems for releasing or dispensing a fluid pressure medium such as carbon dioxide stored in a container, which may be used for extinguishing fires, inflating flotation devices and for other purposes, it is customary to provide the container with a valve, a puncturable disc or other suitable means for releasing the medium from the container when desired, and actuating devices for effecting operation of the releasing means.

The present invention aims to provide an improved device for controlling the initiation and operation of actuating the means whereby the release of the fluid pressure medium from a container is effected.

An object of the invention is to provide an improved device for controlling the release of a fluid pressure medium and which is efficient and positive in operation, simple in construction, economical in manufacture and durable in use.

Another object of the invention is to provide an improved device of the foregoing character which is adapted to be operated either locally or remotely.

Another object of the invention is to provide a control head or device wherein the locally and remotely operable means can be operated independently without either interfering with or impairing the efficiency of the other.

Another object of the invention is to provide a control head or device which can be properly assembled and installed in a minimum length of time by unskilled workmen or operators.

Another object of the invention is to provide a control head or device which, after operation, can be properly reset in a convenient manner for successive operation.

Another object of the invention is to provide a control head having locally and remotely operable means for effecting actuation of the control head mechanism in a manner to release fluid pressure medium from a container and having unidirectional actuated means associated therewith, whereby either the locally or remotely operable means may be independently operated with respect to each other.

A further object of the invention is to provide a device of the foregoing described character wherein both the locally and remotely operable means are provided with manually releasable

2

latching means adapted to discourage unauthorized operation thereof and with means for indicating when one of the operable means has been actuated.

5 A still further object of the invention resides in the construction, arrangement, and operation of the parts of the device, whereby the foregoing objects are accomplished.

Other and further objects of the invention will be obvious upon an understanding of the illustrative embodiment about to be described, or will be indicated in the appended claims, and various advantages not referred to herein will occur to one skilled in the art upon employment of the 10 invention in practice.

A preferred embodiment of the invention has been chosen for purposes of illustration and description and is shown in the accompanying drawings, forming a part of the specification, 15 wherein:

Figure 1 is an elevational view of a control head, illustrating an embodiment of the invention.

Figure 2 is a sectional view, taken on the line 2—2 on Figure 1.

Figure 3 is a sectional view, taken substantially on line 3—3 on Figure 2.

Figure 4 is an elevational view illustrating an actuating element of the control head.

Figure 5 is a detail sectional view, taken on the line 5—5 on Figure 3 and illustrating a cable clamping member.

Figure 6 is a detail sectional view, taken on the line 6—6 on Figure 1.

Figure 7 is a front elevational view, illustrating means for operating the control head from a remote location.

Figure 8 is an elevational view, partly in section, illustrating the control head and the means for operating the same from a remote location.

Figure 9 is a fragmentary view, partly in section of the control head and indicating means therefor.

Referring more particularly to the drawings, 45 there is shown a control head or device suitable for operating or actuating means for releasing a pressure medium from a cylinder (not shown). The device comprises a body having a connecting portion 10 at the lower end thereof and a casing portion 11 mounted on the connecting portion.

The connecting portion 10, preferably, is cylindrical and tubular and carries a connecting nut 12 for attaching the body to a container or to the means for effecting release of a pressure medium from the container. The connecting

portion is provided with an inner bore (Figure 2) comprising a lower chamber 14 and an upper chamber 15 of reduced diameter for housing an annular sealing or packing gland 16. A centrally located aperture or vertical passage 17 extends from the chamber 15 to the lower end of the casing portion 11, for the purpose about to be described.

A suitable pin or rod 19 is mounted in the bore of the connecting portion 10 and extends through the packing gland 16 and the passage 17. The upper end of the pin 19 is adapted to project into the casing portion 11 to be operated by a cam, described hereafter, and the lower end of the pin 19 is adapted to move downwardly of the body to engage and operate suitable means for effecting discharge of the pressure medium in the container. For example, the pin may engage and unseat a pilot valve member for effecting operation of a main valve or may trip a latch for releasing a spring mechanism adapted to in turn operate a cutter for piercing the closure disc on the container. These various means for effecting release of the pressure medium are well known in the art and need not be described in detail.

Preferably, the pin 19 is urged upwardly by a cylindrical helical spring 20 telescoped about the lower portion of the pin 19. The upper end of the spring may abut a washer 21 which bears against a flange 22 on the pin, and the lower end of the spring may be seated on an inwardly extending annular flange 24 of a sleeve member 25 which is suitably secured in the lower chamber 14 of the bore. The extent of upward movement of the pin may be determined by providing a washer 26 intermediate the sleeve member 25 and the shoulder intermediate the upper and lower chambers of the bore. The washer 26 acts as a stop for the flange 22 on the pin.

The casing portion 11 of the body may be integral with the connecting portion, as shown, or may be suitably secured thereto. Preferably, the casing portion comprises a cylindrical casing member 30 which has an end wall 31 and is open at the other end. An annular face 32 is provided adjacent the open end for attaching a suitable cover or closure, about to be described.

The cover or closure, preferably, comprises an outlet or conduit member 34 and a cover member 35 (Figures 2 and 3). The outlet member 34 has a segmental substantially annular base or flange portion 36 adapted to be secured to the annular face 32 in any suitable manner and has a segmental cylindrical skirt or wall portion 37 disposed perpendicularly to the base or flange portion 36. A tubular conduit or nipple portion 39 extends outwardly tangentially from the wall portion 37. The conduit portion is provided with a bore or aperture 40 for passing a pull cable or flexible member 41 into the casing and the bore may be provided with suitable screw threads for attaching a pipe or conduit adapted to shield the cable.

The cover member 35 has a substantially circular cover part 42 providing an end wall for the casing member 30 and has a substantially cylindrical wall or skirt portion 44 which is provided with an outwardly extending substantially annular flange 45. The wall portion 44 and the flange 45 have a recess or cutaway portion providing an opening for receiving the flange portion 36 and the wall portion 37 of the outlet member 34, so that the cover and outlet members cooperate as complementary members to provide a

closure for the open end of the casing member 30. The cover member 35, preferably, is detachably secured to the annular face 32 of the casing member 30, whereby assembly, inspection, and repair of the device is greatly facilitated as will be described hereafter.

An actuator or actuating element (Figures 2, 3 and 4) is housed in the casing for operating the pin 19 and is mounted on a rotatable shaft 47 for rotation therewith, said shaft having one end 47a extending outwardly through a bearing aperture 49 in the end wall 31 and having its other end 47b extending outwardly through a bearing aperture 50 in the cover member 42 of the closure.

The actuating element comprises a cam 46 and a juxtaposed sheave, or drum or pulley 54, the cam (Figure 4) having a cam surface 51 for engaging the pin 19 and moving it downwardly in opposition to the spring 20. Adjacent the cam surface 51, the cam is formed with a circumferentially extending side wall portion 52 for isolating the cam surface 51 from the pulley and, by engagement with the pin, for preventing the cam from being displaced laterally out of engagement with the pin.

In the present instance, the cam and pulley are integrally connected together for unitary rotation with the shaft, the pulley or sheave 54 being formed with a relatively wide circumferential recess or groove 55 for receiving therein the end section of the flexible element or pull cable 41, extending into the casing, the section being wrapped around the sheave and having its free end removably attached thereto.

In Figures 3 and 5 improved means for attaching the cable to the pulley are illustrated. The side wall of the pulley is provided with a slot, groove or recess 56 which, for example, may be elongated or rectangular in shape and has a restricted opening or passage 57 leading to the groove 55 of the pulley. The free end of the cable is secured into a cable clamping member 59 (Figure 5) which may be a rectangular or elongated block having a longitudinal bore or slot 60 for receiving the end of the cable and having a pair of apertures 61 extending transversely through the bore 60. The apertures 61 are screw threaded at one end 62 thereof for receiving suitable screw means, such as set screws or stud screws 64, adapted to engage the cable and force the engaged portions into the other end 65 of the apertures 61 to secure the cable to the block 59. The block 59 is adapted to be seated in the slot 56 so that the end adjacent the restricted opening 57 abuts a shoulder 66 intermediate the slot and the opening 57. The cover member 35, when attached to the casing member 30, is adjacent the side of the pulley and serves to keep the block in the slot. By pulling the cable the portion wrapped around the pulley unwinds and effects rotation of the cam.

In assembling the casing portion of the device, the shaft 47 and the actuating element are introduced into the casing member 30 and with the end 47a of the shaft extending through the bearing aperture 49 in the end wall 31, whereupon, the flange portion 36 of the conduit member 34 is secured to the annular face 32. When the parts are thus positioned, the end of the cable is inserted through the nipple portion 39 of the conduit member and affixed to the block 59. When the block is affixed to the cable, it is inserted within the slot 56 of the pulley and the

latter is rotated sufficiently to reel the end section of the cable thereabout and to position the cam face in a manner to permit the pin 19 to be disposed in its uppermost or non-releasing position. The cover member 35 is then secured to the member 30 and with the end 47b of the shaft extending through the aperture 50 of the cover member, the wall portion 37 of the conduit member closing the recess formed in the skirt portion 44 of the cover member. The construction and arrangement of the parts are such as to permit quick and easy assembly of the device by unskilled workmen or operators in a minimum period of time.

The cable 41 extends from the control head or device to a remote location, such as a control panel or the like, at which location an operator or other suitable means are provided for operating the cable to effect actuation of the control head or device. Such remotely operable means will be described in connection with Figures 7 and 8, hereinafter.

The shaft 47 and actuating element mounted thereon may also be rotated from a local location by a suitable operator. This may be accomplished by pivotally mounting a lever or a manually engageable handle 70 rotatable with respect to the shaft, on the end of the shaft 47a extending outwardly through the bearing aperture 50 in the end wall 31. The handle is provided with a pair of diametrically opposed lugs or projections 71 adjacent the shaft (Figure 1) adapted to engage a pin 72 extending radially through the end 47a of the shaft and having its ends 73 projecting outwardly from the shaft. By swinging or rotating the lever or handle 70 in a clockwise (Figure 1) direction the lugs 71 engage the ends of pins to effect rotation of the shaft.

The handle preferably is attached to the casing portion to prevent accidental movement thereof and to enable the shaft to be rotated by the pull cable independently of the handle. This may be effected by inserting a pin 75, through an aperture 76 in the handle and into a bore 77 formed in the casing member (Figure 2). The pin 75 may be attached to the handle by a seal wire 79 adapted to prevent the pin from falling out of the aperture 76 and the bore 77 and is provided with a finger ring 80 at the outer end for pulling the pin outwardly to break the seal wire and withdraw the pin from the bore 77 and the aperture 76. When the handle is held against movement by the pin, the shaft may be rotated independently of the handle. For example, by pulling the cable the drum or pulley rotates the shaft in a clockwise (Figure 1) direction and the ends 73 of the pin 72 move away from the lugs 71 until the shaft has been turned through about a half revolution. The pins then engage the other sides of the lugs, and the lugs, by reason of the fact that the handle is secured against movement, act as stops to prevent further rotation of the shaft.

It is also desirable to prevent accidental rotation of the cam while the device is being assembled or reset. Suitable resilient locking or latching means may be utilized for this purpose. For example, as shown in Figure 2, a piston or catch member 81 having a rounded head may be mounted in a cap 82 secured in an aperture at the side of the cam member facing the end wall 31. The piston member is urged outwardly from the cam member by a spring 84 and is adapted to be spring pressed into a recess 85

(Figure 6) in the end wall 31 when the cam is in its normal position prior to operation. Upon application of a substantial force to rotate the shaft the piston is adapted to be forced out of the recess. When the cam has been rotated about 135° and the pin 19 is pressed downwardly, the piston is urged into a second recess or well 86 in the end wall 31 to retain the cam in its operating position. Excessive rotation of the cam may be prevented by providing a stop 87 on the side of the cam and adjacent the piston, which engages a stop 89 on the end wall position to stop rotation of the cam when it is rotated into its operating position.

Resetting of the device may be effected by manually rotating the shaft 47 in a counter clockwise direction until the catch member 81 snaps into the recess 85. This may be accomplished by providing an aperture 90 extending through the end 47b of the shaft for receiving a rod member or the like. Also, if desired, the end 47a of the shaft may be provided with a slot 91 for receiving a screw driver or other similar tool for rotating the shaft.

In Figures 7 and 8, there is shown an operator R for operating the control head from a remote location such as a control panel 93. The operator comprises a fitting or sleeve 94 having one end extending through an opening in the panel 93 and having a collar or flange 95 engaging one side of the panel, and a nut 96 threaded on the sleeve 94 and engaging the other side of the panel to secure the sleeve to the panel. The end of the sleeve at the front or control side of the panel is formed with a socket or recessed portion 97 for receiving the shank 98 of a pull-handle 99 or the like which is provided with a bore or recess for securing a shaft or rod 100 slidably mounted in and extending through the sleeve 94.

The end of the shaft 100 at the rear of the control panel extends beyond the sleeve and has connected thereto end portion 101 of the cable 41, the latter being guided over a pulley 102, or several pulleys, if desired, to the control head. The end of the shaft 100 at which the cable is connected is formed with a collar or stop 103 adapted to engage the sleeve 94 when the pull-handle is operated to limit the movement of the shaft so that the cable is pulled a desired distance to effect rotation of the actuating element within the control head.

In order to prevent accidental or unintentional movement of the pull-handle 99 with respect to the sleeve, the shaft 100 is formed with a circumferential groove 104 which receives a pin 105 extending transversely through a bore 106 formed in the sleeve, whereby the shaft is latched to the sleeve. Preferably, the pin 105 is provided with a finger ring 107 to facilitate withdrawing the pin from the sleeve and to thereby unlatch the pull-handle shaft for operation.

Unauthorized operation of the pull-handle is discouraged by a seal wire 108 extending through the finger ring 107 and an aperture in an ear or lug formed on the collar 95 of the sleeve. The seal wire also prevents accidental dislodgment of the pin from the bore 106 in the sleeve and serves to indicate when the pull-handle has been operated or tampered with.

In order to effect rotation of the actuating element of the control head or device by means of the operator R, the pin 105 is withdrawn from the sleeve, and the handle 99 is grasped and pulled in a direction away from the panel. This opera-

tion may be accomplished while the handle or locally operable operator 70 is locked against movement as shown in Figure 2. Likewise, the handle 70 may be operated to rotate the actuating element, while the pull-handle is latched as shown in Figure 8. Thus, either the locally stationed operator or handle 70, or the remotely stationed operator R or pull-handle 98 may be operated independently and without coincident operation of the other operator.

If desired, and as illustrated in Figures 8 and 9, means may be provided for indicating the position of the actuator in the casing. In the present instance, the cover member 35 is formed with a window 115, while the adjacent face of the pulley is provided with a plate 116 having green and red zones 117 and 118, respectively, for observation through the window. The plate 116 is so arranged on the pulley that the green and red zones indicate the inactive and active positions of the actuator, respectively, thus, enabling an observer to be informed as to whether the fluid medium has been released from the container. While the member 35 is shown as being formed with a window and the pulley being provided with the plate, it is to be understood that the member 30 and the cam may be provided therewith, respectively. Furthermore, the zones may be provided with different colors and/or indicia if desired.

From the foregoing description it will be seen that the present invention provides a simple, inexpensive, improved control device which is adapted to be operated locally and remotely. The device is simple in construction and positive in operation. The device can be readily assembled, installed, repaired and inspected and is particularly adapted for installation in crowded quarters where the workman is handicapped by not being able to have the device in full view. The cover for the casing is arranged so that the cable can be conveniently slipped through the conduit piece and then attached to the clamping member which is readily placed into the slot in the pulley. This arrangement insures proper assembly and installation in a minimum amount of time without the aid of special tools or damage to the parts of the device. The device is rugged in construction and can readily withstand any rough usage to which it may be subjected.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

It is also to be understood that the following claims are intended to cover all the generic and specific features of the invention herein described, and all statements of the scope of the invention which, as a matter of language, might be said to fall therebetween.

This application is a continuation-in-part of our prior application filed August 30, 1941, Serial Number 409,110, now abandoned.

We claim:

1. In a device of the class described, the combination of a substantially cylindrical casing member having an open end and an annular end face adjacent the open end, a conduit member having a segmental annular base portion secured to said face and having a segmental cylindrical wall portion provided with a tubular conduit portion; and a cover member for said cas-

ing having a cylindrical wall provided with an opening for receiving said wall of said conduit member and having an annular outwardly extending flange adapted to be attached to said face, said flange having an opening for receiving the base portion of said conduit member.

2. In a device of the class described, the combination of a substantially cylindrical casing member having an open end and an annular end face adjacent the open end, a conduit member having a segmental annular base portion secured to said face, a segmental cylindrical wall portion perpendicular to said base portion and a tubular conduit portion extending tangentially with respect to said wall portion; and a cover member for said casing having a cylindrical wall provided with an opening for receiving said wall of said conduit member and having an outwardly extending annular flange adapted to be attached to said face, said flange having an opening for receiving the base portion of said conduit member.

3. In a device of the class described, the combination of a substantially cylindrical casing member having an open end and an annular end face adjacent the open end, a conduit member having a segmental annular base portion secured to said face and having a segmental cylindrical wall portion provided with a tubular conduit portion, a cover member for said casing having a cylindrical wall provided with an opening for receiving said wall of said conduit member and having an annular outwardly extending flange adapted to be attached to said face, said flange having an opening for receiving the base portion of said conduit member, a cam rotatably mounted in said casing member, a pulley mounted for rotation with said cam and having a recess therein, a cable extending through the tubular conduit portion and about said pulley, and a clamping member attached to the end of said cable and mounted in the recess of said pulley.

4. In a device of the class described, the combination of a body having a slidable member therein and having a casing portion, a rotatable cam in said casing portion having a cam surface for operating said slidable member, a sheave mounted for rotation with said cam, a cable extending about and attached to said sheave for effecting rotation thereof, a shaft rotatable with said cam and sheave carried by said casing portion and having one end thereof extending outwardly from said casing portion, a member extending radially outwardly from the outwardly extending end of said shaft, and a manually engageable lever rotatably mounted on the outwardly extending end of said shaft adjacent said radially extending member, said lever having a projection for engaging said radially extending member to effect rotation of said shaft upon rotation of said lever about said shaft.

5. In a device of the class described, the combination of a body having a slidable member therein and having a casing portion, a rotatable cam in said casing portion having a cam surface for operating said slidable member, a sheave mounted for rotation with said cam, a cable extending about and attached to said shaft for effecting rotation thereof, a shaft rotatable with said cam and sheave and carried by said casing portion with end extending outwardly thereof, a pin extending radially through said shaft at the outwardly extending end to provide diametrically opposite engageable portions on said shaft,

and a manually engageable handle member rotatably mounted on the outwardly extending end of said shaft adjacent said pin, said handle member having a pair of diametrically opposite projections for engaging the portions of said pin and effecting rotation of said shaft upon rotative movement of said handle about said shaft.

6. In a device of the class described, the combination of a body having a slidable member therein and having a casing portion, a rotatable cam in said casing portion having a cam surface for operating said slidable member, a sheave mounted for rotation with said cam, a cable extending about and attached to said sheave for effecting rotation thereof, a shaft rotatable with said cam and sheave carried by said casing portion and having one end thereof extending out of said casing portion, a member extending radially outwardly from the outwardly extending end of said shaft, a manually engageable lever rotatably mounted on the outwardly extending end of said shaft adjacent said radially extending member, said lever having a projection for engaging said radially extending member to effect rotation of said shaft on rotative movement of said lever about said shaft, and means for attaching said lever to said portion and preventing rotation thereof, said means being adapted to be manually released.

7. In a device of the class described, the combination of a body having a slidable member therein and having a casing portion, a rotatable cam in said casing portion, having a cam surface for operating said slidable member, a sheave mounted for rotation with said cam, a cable extending about and attached to said sheave for effecting rotation thereof, a shaft rotatable with said cam and sheave and carried by said casing portion with one end extending outwardly thereof, a pin extending radially through said shaft at the outwardly extending end to provide diametrically opposite engageable portions on said shaft, a manually engageable handle member rotatably mounted on the outwardly extending end of said shaft adjacent said pin, said handle member having a pair of diametrically opposite projections for engaging the portions of said pin and effecting rotation of said shaft upon rotative movement of said handle about said shaft, and means for attaching said handle member to said casing portion to prevent movement of said handle member, said means being adapted to be manually released.

8. In a device of the class described, the combination of a body having a slidable element therein and having a casing portion provided with an end wall, a rotatable cam member in said casing portion having a cam surface for operating said slidable element, a sheave member mounted for rotation with said cam member, and a pull cable extending about said sheave member for effecting rotation thereof, one of said members and said end wall having cooperating spring urged latch means and latch receiving means for preventing accidental rotation of said cam and sheave members.

9. In a device of the class described, the combination of a body having a slidable element therein and having a casing portion provided with an end wall, a rotatable cam member in said casing portion having a cam surface for operating said slidable element, a sheave member mounted for rotation with said cam member, and a pull cable extending about said sheave member for effecting rotation thereof, one of said members

carrying a spring urged projection extending outwardly toward the end wall of said casing portion, and said casing end wall having a recess for receiving said projection when said cam and sheave members are in set position and having a second recess for receiving said projection when said cam member has been operated to latch the cam and sheave members in operated position, whereby the cam surface is maintained in a position to operate said slidable element.

10. In a device of the class described, the combination of a body having a slidable member therein and having a substantially cylindrical casing portion provided with an end wall, a rotatable shaft disposed in said casing portion, a cam member on said shaft having a cam surface for operating said slidable member, a sheave member on said shaft mounted for rotation with said cam member, and a pull cable extending about said sheave member for effecting rotation thereof, said cam member carrying a spring urged projection extending outwardly toward the end wall of said casing portion, and said casing end wall having a recess for receiving said projection when said cam and sheave members are in a set position and having a second recess for receiving said projection when said cam member has been operated to latch the cam and sheave members in operated position, whereby the cam surface is maintained in a position to operate said slidable member.

11. In a device of the class described, the combination of a casing, a shaft rotatably disposed in said casing and having one end thereof extending outwardly from said casing, a sheave in said casing mounted for rotation with said shaft, a cable extending about and attached to said sheave for effecting rotation thereof, a member extending radially from the outwardly extending end of said shaft, and a manually engageable lever rotatably mounted on the outwardly extending end of said shaft adjacent said radially extending member, said lever having a projection for engaging said radially extending member to effect rotation of said shaft upon rotative movement of said lever about said shaft.

12. In a device of the class described, the combination of a casing, a shaft rotatably disposed in said casing and having one end thereof extending outwardly from said casing, a sheave in said casing mounted for rotation with said shaft, a cable extending about and attached to said sheave for effecting rotation thereof, a member extending radially from the outwardly extending end of said shaft, a manually engageable lever rotatably mounted on the outwardly extending end of said shaft adjacent said radially extending member, said lever having a projection for engaging said radially extending member to effect rotation of said shaft upon rotative movement of said lever about said shaft, and means for attaching said lever to said casing and preventing rotation thereof, said means being adapted to be manually released to facilitate operation of said lever.

13. In a device of the class described, the combination of a body having a slidable member therein and having a casing portion, a shaft rotatably disposed in said casing portion and having one end thereof extending outwardly from said casing portion, a cam in said casing portion mounted on said shaft for rotation with said shaft and having a cam surface for operating said slidable member, a member extending radially outwardly from the outwardly extending end of said shaft, a manually engageable lever

11

rotatably mounted on the outwardly extending end of said shaft adjacent said radially extending member, said member having a projection for engaging said radially extending member to effect rotation of said shaft upon rotative movement of said lever about said shaft, and means for rotating said shaft independently of the operation of said lever.

14. In a device of the class described, the combination of a substantially cylindrical casing member having an open end provided with a substantially annular end face, a conduit member having a base portion secured to said end face and having a wall portion provided with a tubular conduit portion, and a cover member for said casing member having a substantially annular base portion attached to said end face and having a substantially cylindrical wall portion, said base and wall portions of said cover member being provided with recesses adapted to accommodate said conduit member.

15. A pulley casing comprising a casing member having an open end, a conduit member having a wall portion provided with a tubular conduit portion, means for attaching said conduit member to said casing member at said open end, a cover member for said casing member having a wall portion provided with a recess adapted to accommodate the wall portion of said conduit member and means for attaching said cover member to said casing member at said open end.

16. A pulley casing comprising a casing member having an open end, a conduit member having a wall portion provided with a tubular conduit portion, means for attaching said conduit member to said casing member at said open end, a cover member for said casing member having a wall portion provided with a recess adapted to accommodate the wall portion of said conduit member, means for attaching said cover member to said casing member at said open end, a pulley mounted for rotation in said casing member and having a recess therein, a cable extending about said pulley, and a member secured to said cable and disposed in said pulley recess to attach said cable to said pulley.

17. In a device of the class described, the combination of a sheave mounted for rotation, said sheave having a groove and having an end face provided with a recess which has a restricted portion at one end thereof leading to the groove of said sheave, an elongated cable clamping member removably positioned in said recess and having a longitudinal slot therein, a pulley cable ex-

12

tending around said sheave and lying in the groove thereof and having its free end extending through the restricted end of said recess and disposed in said slot, and means attached to said clamping member for securing the free end of said cable in said slot.

18. A pulley casing comprising a casing member having an open end, a conduit member having a wall portion provided with an outlet portion, means for attaching said conduit member to said casing member at said open end, a cover member for said casing member having a wall portion provided with a recess adapted to accommodate the wall portion of said conduit member and means for attaching said cover member to said casing member at said open end.

19. A pulley casing comprising a casing member having an open end, a conduit member having a wall portion provided with an outlet portion, means for attaching said conduit member to said casing member at said open end, a cover member for said casing member having a wall portion provided with a recess adapted to accommodate the wall portion of said conduit member, means for attaching said cover member to said casing member at said open end, a pulley mounted for rotation in said casing member, and a cable member extending about said pulley and through said outlet portion, said cable member being secured to said pulley.
